PLAYING CARD SEPARATOR

Mike A. Proctor, Tucson, Ariz.

Application October 31, 1934, Serial No. 750,883

2 Claims. (Cl. 273—149)

The invention relates to a playing cards separator and more especially to a device for shuffling playing cards.

The primary object of the invention is the provision of a device of this character, wherein a deck or pack of cards can be placed therein so that the cards of the deck or pack will be separated into groups displaced from each other, whereby on manual manipulation of the cards the shuffling of the deck or pack can be had and thus eliminating the hand shuffling as is conventional.

Another object of the invention is the provision of a device of this character, wherein the same is of novel construction and is portable so as to render it convenient for use upon a card table and which will enable the separation of the cards of the deck or pack for the shuffling thereof with dispatch and without the bending or damaging of the cards resultant from hand shuffling or separation.

A further object of the invention is the provision of a device of this character which is simple in construction, thoroughly reliable and effective in its purposes, convenient for the shuffling of playing cards, strong, durable, and inexpensive to manufacture.

With these and other objects in view, the invention consists in the features of construction, combination and arrangement of parts as will be hereinafter more fully described in detail, illustrated in the accompanying drawing, which discloses the preferred embodiment of the invention, and pointed out in the claims hereunto appended.

In the accompanying drawing:

Figure 1 is a vertical longitudinal sectional view through the device, showing the same constructed in accordance with the invention and a deck or pack of playing cards placed therein for the separation of the cards of the deck or pack to enable shuffling of the same with dispatch.

Figure 2 is a sectional view on the line 2—2 of Figure 1 looking in the direction of the arrows.

Figure 3 is a perspective view of one of the separator blades.

Figure 4 is a perspective view of a spacer for the separator blades of the device.

Figure 5 is a fragmentary vertical longitudinal sectional view showing a slight modification.

Figure 6 is a vertical transverse sectional view of the latter.

Figure 7 is a fragmentary vertical sectional view of a still further modification.

Figure 8 is a side view of a further modification.

Figure 9 is an end elevation thereof.

Figure 10 is a fragmentary vertical transverse sectional view of a still further modification.

Figure 11 is a fragmentary perspective view of the construction as shown in Figure 7.

Similar reference characters indicate corresponding parts throughout the several views in the drawing.

Referring to the drawing in detail, particularly Figures 1 to 4 inclusive which are illustrative of the preferred construction of the invention, A designates generally a base, in this instance the same being in the form of a sheet metal hollow slab to provide a flat top 10 and a rim 11 marginally thereof. The base A is preferably of substantially rectangular shape, 20

although it may be of other configuration. Formed centrally in the top 10 of the base A is an opening, walled at opposite ends through the medium of the flanges 12 as cut and bent from the said top 10 of the base A. Adapted 25

to be located within the opening in the top 10 between the flanges 12 is a series of spaced separator blades 13, these being parallel with each other and rising vertically above the base uniformly to a determined height. The separator blades 13 are spaced from each other by 30

spacer blocks or members 14, these being fitted upon a tie bolt 15 which is also passed through notches 16 as provided in the separator blades 13, the bolt being engaged in the flanges 12 and carrying a nut 17 for the securing of such bolt in place.

The separation of the blades 13 is such as to permit accommodation of one or several playing cards of a deck or pack when the latter is 40 superimposed over the separator blades 13, with other of the cards resting upon the upper edges of the said blades 13 and in this fashion the groups 18 and 19, respectively, of cards of the

deck or pack will be separated so that by grasping the projected cards of the group 19 this group may be withdrawn from the group 18 for the convenient and easy shuffling of the deck or pack of cards with dispatch. The operation as before explained may be repeated for a thorough 45

shuffling of the deck or pack of cards.

The deck or pack of cards in its original position can be grasped either in the right or left hand at opposite edges of the cards of the deck or pack so as to hold the same true in stacked 50 55

condition and in this condition the said deck or pack can rest upon the base A so that when it is desired to shuffle the cards the deck or pack may be readily and easily grasped to have the cards thereof relatively loose, whereupon on placing the deck or pack in such condition over the blades 13 the cards of the deck or pack will become automatically separated into groups, as will appear from Figures 1 and 2 of the drawing, for the convenient shuffling of such cards.

In Figures 5 and 6 of the drawing there is shown a slight modification, wherein the base 20 of the device is made solid and has the space 21 for the blades 22, these resting upon a bed plate 23 as counterseated in the under face of the base 20 and fastened thereto by the fasteners 24. These blades 22 are united with each other and held secure to the bed plate 23 by welding, solder, cement or the like, as at 25, this being contained within notches 26 therefor as provided in the respective blades.

In Figure 7 of the drawing there is shown a further modification of the invention, wherein the separator blades 27 are spaced from each other through the medium of a filler 28 as arranged therebetween and this filler may be solder, cement or the like.

In Figures 8 and 9 of the drawing there is shown a still further modification, wherein the separators are in the form of wire wickets 29, these being spaced from each other an equidistance and held within a base 30 in any suitable manner so as to rise vertically from the top of said base uniformly with relation to one another.

In Figure 10 of the drawing there is shown a still further modification, wherein each separator is in the form of the wicket 31 having the half-circular upper end 32.

It is, of course, to be understood that the separators in the form of the blades or wickets can be mounted in any desirable manner in a base so as to be uniformly spaced one from the other and to have such separator parts extend uniformly in a vertical direction above the top of the base or bed for the convenient separation of playing cards to avoid the hand shuffling of such cards, which results in the bending, mutilation or other damage thereto.

What is claimed is:

1. A device of the character described comprising a hollow slab having an opening through its top, flanges depending from said top at opposite sides of the opening, a plurality of blades fitted within the opening and extending perpendicularly above the top, spacer blocks interposed between the blades for spacing the same uniformly from each other and having their upper edges substantially flush with the top, and a bolt passed transversely through the blades, blocks and flanges to hold the said blades and blocks grouped together and fast in the base.

2. A device of the character described comprising a base forming a flat slab having an opening therein extending through the top and bottom faces of said base, a plurality of separator blades fitted within the opening and extending vertically above the base, spacer blocks interposed between the blades and having their upper edges substantially flush with the top of the base, a plate counterseated in the bottom face of the base and providing a rest for the said blades and blocks, the blades and blocks being provided with notches in opposite side edges thereof and in alignment with each other and means within the notches for uniting the blocks and blades with each other.

MIKE A. PROCTOR.
